UNITED STATES PATENT OFFICE

2,617,555

HYDRAULIC EQUALIZER

Le Roy M. Davis, Glen Ellyn, Ill.

Application September 29, 1948, Serial No. 51,836

7 Claims. (Cl. 220—85)

1

My invention relates, generally, to hydraulic equalizers, and it has particular relation to devices for neutralizing the unbalanced static force acting on a container holding fluid, such as the water box of a steam condenser, due to openings in the container walls for inlet and discharge pipes.

This unbalanced force is equal to the product of the unit pressure at the opening in the container and the area of the opening. Where the pressure is relatively low, or where the area of the opening is relatively small, or when container is rigidly supported, this force may be neglected.

However, this force may become a factor which must be taken into consideration in certain instances. For example, in the majority of cases where a steam condenser is employed in conjunction with a steam turbine, the condenser is not rigidly supported by its foundation, but is welded or bolted to the turbine exhaust flange with only a portion of its weight being transmitted by coil springs to the condenser foundation; the remaining weight going to the turbine foundation by means of the turbine housing. Due to temperature changes the condenser, being rigidly supported from above, moves in a vertical direction an appreciable amount, thus making it necessary to provide expansion joints in the cooling water intake and outlet pipes. Since the expansion joints are incapable of transmitting force, the unbalanced force due to the pipe opening in the condenser's water box will result in a moment acting on the turbine housing which, in turn, may cause distortion adversely affecting operation of the moving parts of the machine, or if extreme, result in a mechanical failure of the turbine. The diameter of the cooling water intake or outlet may be of the order of from forty to fifty inches. The water may be circulated through the condenser at a pressure as high as seventy pounds per square inch. Thus the force involved may be of the order of from 88,000 to 137,500 pounds in these particular circumstances.

The force acts in one direction or the other depending upon whether the pressure within the container is above or below atmospheric pressure. Thus, if the container is operating under a vacuum, the force acts oppositely to that in which it acts if the pressure within it is above atmospheric pressure.

It has been proposed to counteract this unbalanced force on the condenser by introducing an equal force acting in the opposite direction

2

and whose reaction acts against a fixed support, such as a pier or wall of a building. Such an arrangement would be, in reality, a hydraulic jack with a piston area equal to the area of the opening in the condenser's water box and with the unit pressure of the fluid in the jack equal to the unit pressure of the fluid in the condenser's water box at the opening. This hydraulic jacking device must be placed diametrically opposite the opening in the condenser's water box and a fixed support must be provided to take the reaction. Such an arrangement has serious disadvantages since it may be difficult, if not impossible, to provide the fixed support for taking the reaction. The cost of a fixed support to take forces of the magnitude mentioned previously will be a big item of expense. In the conventional divided water box it is impossible to place the hydraulic jacking device opposite the opening, since the two inlet pipes and the two outlet pipes are placed diametrically opposite one another.

The object of my invention is to provide a self-contained hydraulic equalizer for a condenser or a like fluid container to automatically counteract an unbalanced static force resulting from an opening in the condenser's water box, using the hydraulic jack principle, but directing the reaction so that it acts on the wall of the condenser rather than requiring a separate fixed support, the device being located at the bend in a pipe communicating with the condenser and having an expansion joint between the bend and the condenser so that the direct force of the hydraulic equalizer exactly balances the hydraulic force acting on the bend in a coaxial direction with the pipe and condenser pipe opening and further to apply the concepts of my invention where the bend in the pipe is 90° or less or with a straight pipe having no bend therein.

Other objects of my invention will, in part, be obvious and in part appear hereinafter.

My invention is disclosed in the embodiments thereof shown in the accompanying drawings, and it comprises the features of construction, combination of elements and arrangement of parts which will be exemplified in the constructions hereinafter set forth and the scope of the application of which will be indicated in the appended claims.

For a more complete understanding of the nature and scope of my invention, reference can be had to the following detailed description,

taken together with the accompanying drawings, in which:

Figure 1 is a top plan view of a hydraulic equalizer constructed in accordance with my invention and illustrating how it may be connected to a condenser only a part of which is shown;

Figure 2 is a view, in front elevation, of the hydraulic equalizer shown in Figure 1, there being shown a hydraulic equalizer for both the inlet and outlet pipes for the condenser;

Figure 3 is a view, somewhat diagrammatic in character, illustrating how the chamber formed by the second expansion joint and the pressure plate can be connected directly to the container or condenser so that the pressure therein will be applied in the chamber rather than the reduced pressure existing in the pipe at the bend resulting from the drop due to the velocity of fluid flow in the pipe;

Figure 4 is a top plan view of another embodiment of my invention in which the hydraulic equalizer is applied to a pipe making a bend less than ninety degrees;

Figure 5 is a detail sectional view taken along the line 5—5 of Figure 4; and

Figure 6 illustrates, somewhat diagrammatically, how my invention can be incorporated in conjunction with a straight run of pipe for equalizing the force at the opening in a container.

Referring now particularly to Figures 1 and 2 of the drawings, it will be observed that the reference character 10 designates, generally, a condenser which may be employed in conjunction with a steam turbine for receiving, cooling and condensing the steam exhausted therefrom. In order to accomplish this, cooling water is circulated through the condenser 10. For this purpose the condenser 10 is provided with intake openings 11 and discharge openings 12 which may be located opposite each other as illustrated in Figure 2. The openings 11 and 12 may have a diameter of forty-eight inches and the pressure within the condenser 10 at which the water is circulated therethrough may be of the order of seventy pounds per square inch. It will be understood that the particular sizes and pressures referred to herein are for illustrative purposes. Other types and sizes of condensers can be employed with other sizes of intake and discharge openings and other pressures may be employed. Moreover, instead of water, a gas may be employed as the fluid in the container 10. In some cases the pressure may be below atmospheric pressure at the discharge opening 12. However, since the present invention has been applied successfully in conjunction with condensers for use with steam turbines, the details of its application thereto will be set forth herein.

In the particular condenser 10 shown in Figure 2, it is contemplated that the cooling water will be circulated through both of the intake openings 11 and out of the discharge openings 12 at the same time and that the intake and discharge pressures will be equal on both sides of the condenser. Accordingly, under these conditions, the forces tending to move the condenser 10 are balanced and can be disregarded. However, it may be the case that it may be necessary to interrupt the flow of cooling water through one of the intake openings 11 and drain one side of the condenser 10, the water passages being separated by closing valve 10'. As a result, under these conditions the static force tending to move the condenser 10 will be equal to the

arithmetic sum of the pressures at the inlet and outlet openings times their respective areas. This force may be sufficient in some cases to move the condenser 10 sufficiently to rupture the connection between it and the turbine or to distort the turbine housing causing operating difficulties, or to move it slightly from its foundations. It is to neutralize such a static force that the present invention is particularly addressed.

It will be noted that short lengths of pipe 13 and 14 extend from the intake and discharge openings 11 and 12 and that they terminate in flanges 13' and 14'. Standard practice in the past has been to provide expansion joints, shown generally at 15, between the short lengths of pipe 13 and 14 and intake and discharge pipes 16 each of which has a ninety degree bend that is indicated, generally, at 17 in Figure 1. The intake and discharge pipes 16 may be supported rigidly by a framework 18 and also by a wall 19 through which they extend. The expansion joints 15 permit the condenser 10 to move slightly without affecting the fixed location of the rigidly held intake and discharge pipes 16. Also the expansion joints 15 prevent the application of the forces just referred to to the pipes 16.

It will be observed that each of the expansion joints 15 terminates in flanges 20 which are secured by suitable means to flanges 21 and 22 located respectively at the ends of short sections of pipe 23 and 24 and the intake and discharge pipes 16.

As illustrated in Figure 1, the outside surface 25 of the bend 17 in the pipe 16 has applied thereto a strut 26 in the form of a pipe which, at its other end, bears against a blind flange 27. The blind flange 27 bears against a flange 28 of a second expansion joint 29 which corresponds in size to the expansion joint 15. The expansion joint 29 also has a flange 28 at its other end which bears against a flange 30 that is located at the outer end of a short length of pipe 31. The pipe 31 has an internal diameter which is the same as the internal diameter of the pipe 16. Its outer end is closed by a pressure plate 32. It will be understood that the area of the pressure plate 32 within the short length of pipe 31 is equal to the area of the intake or discharge opening 11 or 12 in the container or condenser 10. It is noted here that a chamber, shown generally at 33, is formed by the blind flange 27, expansion joint 29, short length of pipe 31 and the pressure plate 32. The chamber 33 will be referred to hereinafter in pointing out how my invention functions.

It will be understood that the static pressure exerted by the water within the pipes 16 also is applied to the inner surface of the bend 17 on the side opposite the surface 25. In order to permit the force on bend 17 to counterbalance the equal and opposite force acting on blind flange 27, the strut 26 is provided as described. In addition, reinforcing plates 36 extend between the bend 17 and the blind flange 27 for the same purpose.

Within each of the pipe struts 26 there is a conduit 37 which extends from the blind flange 27 into each of the pipes 16. It will be understood that each conduit 37 places the associated chamber 33 in communication with the interior of the corresponding pipe 16 and that the chamber 33 is filled with fluid, water in this particular case. The pressure exerted within each of the chambers 33 is the same as exists in the corresponding pipe 16.

In some instances it may be found that the pressure at bend 17 due to velocity and friction losses is somewhat less than the pressure in the container 10. Where it is desired to have the same pressure within the chamber 33 that is present within the container 10, the conduit 38, Figure 3, can be employed. It will be observed that the conduit 38 extends from the chamber 33 into the container or condenser 10. In most instances, the kinetic energy due to velocity of the fluid in pipe 16 may be discounted as compared to the static forces within the condenser 10 due to static pressure.

From what has been said it will be apparent that a force is exerted on the pressure plate 32 which is equal to the force that is exerted on the container or condenser 10 as a result of the static pressure released by the intake opening 11 or discharge opening 12. It remains to show how this force applied to the pressure plate 32 is equalized in accordance with my invention.

For this purpose three or more combination tension and compression members, shown generally at 39, may be provided. As shown in Figure 2, each of these members comprises a sleeve or pipe 40 which is adapted to resist compression and a rod 41 extends therethrough that is threaded at both ends and is adapted to resist tensile stresses. Nuts 42 are threaded onto the ends of the rods 41 to hold them in position. As shown in the drawings the members 39 extend between the pressure plate 32 and a ring 43. Each ring 43 is secured as by welding to the adjacent end of each short pipe section 23 and 24 and is secured as by bolts to the adjacent flanges 13' and 14'. Trapezoidal reinforcing plates 44 extend between the rings 43 and the flanges 21 at the other ends of the pipe sections 23 and 24. Instead of connecting the tension-compression members 39 to a separate ring 43, they may be connected directly to the shell of the condenser 10. However, where the present invention is added to a condenser piping system that has been installed previously with the expansion joints 15 in place, I have found that it is advantageous to employ the particular construction just described.

It will be apparent now that the force due to static pressure which acts on the condenser 10 as a result of the presence of either of the openings 11 or 12 is automatically equalized by the provision of the chamber 33 and the tension-compression members 39 which serve to apply the force acting on the pressure plate 32 to the container or condenser 10 either directly or through the agency of the ring 43 or its equivalent construction. Since the unbalancing effect of each of the openings 11 and 12 is automatically self-compensated, there is no resultant force tending to move the container or condenser 10.

In Figures 4 and 5 of the drawings, a modification of my invention is illustrated in which the bend 17' in the pipe 16 is less than ninety degrees. Specifically, the bend 17' is at an angle of thirty-three degrees thirty minutes.

The outside surface 25' of the bend 17' is engaged by one end of a strut 26' which, like that described hereinbefore, may be in the form of a pipe. In addition, plates 48 may extend radially from the pipe 26', as shown more clearly in Figure 5, for the purpose of distributing the force more fully over the outside surface 25'.

If desired a shut-off valve, shown generally at 49, may be provided between the ring 43 and the short length pipe 13. It will be understood, of course, that the valve 49 may be omitted. Also,

in both of the embodiments of the invention shown in Figures 1 and 2 and 4 and 5 a drain valve 50 may be provided in a suitable pipe which extends from a suitable aperture in the pressure plate 32. The valve 50 is provided, as will be understood readily, to permit the chamber 33 to be drained if desired.

In the embodiments of the invention which have been described, it will be understood that the same pressure is present within the chamber 33 that is present either in the pipes 16 or in the condenser 10 depending upon the location of the conduit 37 or 38. At any event, it is desired that substantially the same pressure be applied within the chamber 33 that is present within the condenser 10. This pressure within the chamber 33 reacts in one direction against the blind flange 27 and through the strut 26 and plates 36 or the strut 26' and the plates 48 to equalize the pressure applied on the inside surface of the bend 17 or 17'. This same force also acts in the opposite direction against the pressure plate 32. By means of the tension-compression members 39, the force acting on the pressure plate 32 is transferred to the condenser 10 so that there is no net force reacting on it which would tend to effect its movement.

In Figure 6 of the drawings I have shown a construction for equalizing the force otherwise applied to a condenser 10 where the intake pipe 16 does not have a bend close to the container 10 but rather there is a substantial length of straight run of the pipe. The showing here is somewhat diagrammatic. It will be observed that a collar 52 is fastened onto the pipe 16 beyond the expansion joint 15. Struts 53 extending angularly from the pipes 16 and collar 52 serve to react against the same and against blind flanges 27 of a pair of expansion joints 29 which are interposed between the blind flanges 27 and a pair of pressure plates 32. This provides two chambers 33 within which the pressure is maintained through conduits 37 to be equal to the pressure within the pipes 16 or within the container 10. The construction is such that the sum of the areas of the pressure plates 32 to which the fluid pressure is applied is equal to the area of the opening 11 in the container 10 and the effective center of action of the hydraulic forces acting on pressure plates 32, as if such forces were resolved to a single force, lies on the central axis of opening 11. The sets of tension-compression members 39, preferably three in each set, serve to interconnect each of the pressure plates 32 with the condenser 10.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

I claim as my invention:

1. For use with a condenser carrying fluid under pressure for the purpose of counteracting unbalanced internal static forces present within said condenser resulting from placing an inlet opening in one wall thereof for the introduction of a flexible inlet pipe or the like, a hydraulic equalizer comprising, a pair of spaced side-by-side pressure plates disposed externally of said condenser, opposite and parallel to said opening therein; an expandable pressure chamber disposed between said plates, a pressure transmit-

ting conduit interconnecting said pressure chamber and the interior of said condenser, and a plurality of tension compression members connecting one of said pressure plates and said condenser whereby the static hydraulic forces within said condenser may be balanced by the static forces acting on said one pressure plate.

2. For attachment to a condenser carrying pressurized fluid wherein an opening has been formed for the reception of suitable piping thereby creating an unbalanced static force within said condenser, a hydraulic equalizer comprising in combination, an inlet pipe received in said opening formed in said condenser, one end thereof being rigidly secured to said condenser and the other end thereof rigidly secured at a point remote from said condenser; a transversely disposed expansion joint in said pipe, a pair of pressure plates disposed in spaced parallel relation opposite said opening in said condenser exteriorly of said pipe and condenser, an expandible pressure chamber disposed between and communicating with said two plates, rigid connecting members between the exterior of said pipe and one of said plates, rigid tension compression members connecting the second of said plates with said condenser, and a pressure transmitting conduit communicating between the interior of said pipe and said pressure chamber, whereby the static hydraulic pressure within said condenser may be transmitted along said pipe and conduit to said pressure chamber so that the force thereby exerted on said pressure plate connected with said condenser may oppose the unbalanced static force exerted within said condenser.

3. For use with a condenser containing fluid under pressure and in which an opening is formed resulting in the application of an unbalanced static force to said condenser tending to move the same, a hydraulic equalizer comprising in combination, a pipe receivable in said opening and having an expansion joint interposed therein, a pressure plate positioned exteriorly of said pipe and said condenser, strut means bearing, at one end, against said pipe beyond said expansion joint therein and at the opposite end against a blind flange member, a second expansion joint interposed between said pressure plate and said blind flange member and forming a fluid tight chamber therewith, conduit means communicating between said chamber and said condenser to transmit the static pressure within the latter to said chamber and said pressure plate, and retaining tension rod and compression sleeve means connecting said plate to said condenser in a manner to transmit force exerted on said plate from said pressure plate to said condenser whereby said unbalanced static force in the latter is neutralized.

4. The invention, as set forth in claim 3, wherein said pressure plate is opposite and parallel to said opening in said condenser and said retaining rod and sleeve means extend at right angles to and between said pressure plate and said condenser.

5. For use with a condenser holding a body of pressurized fluid and in which an opening is formed resulting in the application of an unbalanced static force to said condenser, the combination comprising, a pipe member, having an expandible joint and a bend portion interposed therein, communicating with said condenser via said opening therein; a pressure plate positioned exteriorly of said pipe and condenser, strut means

bearing at one end against the exterior surface of said pipe at said bend therein; the interior surface of said bend having said unbalanced force applied thereto, a blind flange member mounted at the other end of said strut means, a second expansion joint interposed between said flange and said pressure plate and connected therewith to provide a fluid tight chamber therewith, conduit means communicating with said chamber and said pipe for transmitting fluid pressure within said pipe to said chamber whereby said unbalanced force on said bend is counterbalanced by force exerted on said flange by said fluid pressure and transmitted to said pipe bend via said strut means, and retaining rod and sleeve means rigidly connecting said plate to said condenser for transmitting to said condenser force exerted on said plate by said fluid pressure for neutralizing said unbalanced static force thereon.

6. For use with a condenser holding a fluid under pressure and in which an opening is formed resulting in the application of an unbalanced static force to said condenser, a hydraulic equalizer comprising in combination, a straight pipe received at one end in said opening in said condenser and anchored rigidly at its opposite end, a collar member rigidly mounted about said pipe, an expansion joint interposed in said pipe intermediate said collar member and said opening, at least two pressure plates positioned symmetrically on opposite sides of said pipe exteriorly of said condenser, at least two strut means mounted at one end to and disposed angularly outward from said collar, a blind flange member mounted at the opposite end of each of said strut means, parallel to and spaced from one of said plates, expansion joint means interconnecting each of said flange members with one of said plates to form two fluid tight chambers, conduit means communicating with said chambers and the interior of said pipe for transmitting fluid pressure within the latter to said chambers, and rigid tension and compression retaining members interconnecting said pressure plates with said condenser whereby said unbalanced static force within the latter is neutralized by the forces exerted on said plates.

7. The structure as set forth in claim 6, wherein in the sum of the effective areas of said pressure plates acted upon by said fluid pressure is equal to the area of said opening in said condenser and the effective center of action of the hydraulic forces exerted on said pressure plates lies on the central axis of said opening.
